UNITED STATES PATENT OFFICE.

FREDERICK GROVER, OF LEEDS, ENGLAND, ASSIGNOR TO THE FORGROVE MACHINERY COMPANY LIMITED, OF LEEDS, ENGLAND.

TABLET-WRAPPING MACHINE.

1,110,133.

Specification of Letters Patent.

Patented Sept. 8, 1914.

Application filed July 8, 1913. Serial No. 777,806.

To all whom it may concern:

Be it known that I, FREDERICK GROVER, a subject of the King of Great Britain, residing at Leeds, in the county of York, England, have invented certain new and useful Improvements in Tablet-Wrapping Machines, of which the following is a specification.

This invention refers to wrapping machines for folding wrappers around rectangular tablets, such as cakes of soap, and particularly to a machine of that type by which the tablet is wrapped in a first or inner wrapper, and then in a second or outer wrapper and delivered from the machine.

The subject matter of the present invention will be hereafter described with reference to Figures 1 to 31 of the accompanying drawings, of which Figs. 4 to 16 show in perspective a tablet in the various stages of wrapping, and in order to render perfectly clear the functions which this machine is to perform, the wrapping of the tablet at Figs. 4 to 16 will be firstly described.

The machine according to the present invention is for dealing with rectangular tablets, and to simplify the following description it will be presumed that the tablet A, Fig. 4, to be wrapped, is oblong and so presents a top and bottom surface, two ends and two sides, and the following operations are to be effected: The unwrapped tablet A, Fig. 4, with a rectangular wrapper B upon its top surface, is carried up by a plunger between two stationary vertical guide plates by which the projecting ends B¹, B² of the wrapper are folded vertically downward and caused to cover the ends of the tablet, as at Fig. 5; proceeding upward the tablet passes between downwardly extending vertical guide plates depending from a longitudinally reciprocative carriage, by which guide plates the overhanging sides C of the wrapper are folded down on to the sides of the tablet, the wrapper being of such width that the sides of the tablet are covered by the wrapper. While so held a slide passes beneath one end of the tablet and folds the overhanging end B¹, Fig. 6, of the wrapper on to the lower surface of the tablet and tucking fingers advance and fold in the corner pieces D, Fig. 6, against the sides of the tablet, as at E Fig. 7.

An advance of the reciprocative carriage 55 carries the forward depending end B² of the

wrapper over the upper surface of one of the guide plates and folds the end B² of the wrapper on to the lower surface of the tablet as at Fig. 8, so that it overlaps the first fold thereon and a further advance of the carriage, still carrying the partly wrapped tablet, brings the forward corner pieces F, Fig. 8, of the wrapper to meet with tucking fingers which tuck in the second corner folds F of the wrapper on to the sides of the tablet as at Fig. 9. Plungers then seize the tablet and carry it downward on to the upper surface of the second wrapper H as at Fig. 9, and between vertical surfaces by which the sides H¹, H², Fig. 10, of the wrapper are folded upward on to the sides of the tablet, the outstanding flaps J, Fig. 9, of the inner wrapper being simultaneously brought up against the sides of the tablet. A top slide then folds the rear upstanding side H² of the wrapper on to the top surface of the tablet as at Fig. 11, and it is forced beneath an overhanging member which folds the second side H¹ of the wrapper on to the top surface of the tablet as at Fig. 12. Folding fingers 80 then pass downward and fold the projecting upper ends H² of the wrapper on to the ends of the tablet, Fig. 13, and on to the projecting lower ends H¹ of the wrapper. A forked slide then effects the first tuck K, Fig. 14, of the corners of the second wrapper on to the ends of the already wrapped tablet. The tablet is then passed along through a trough during which the second corner tucks L, Fig. 15, are made in the corners of the wrapper, and finally the remaining projecting flaps M, Fig. 15, of the wrapper are turned beneath the base of the tablet, leaving the latter as shown at Fig. 16. It will thus be observed that both the outer and inner wrappers to be employed are of rectangular shape, and that when the wrapping operation is completed the first wrapper has become folded on to the tablet in a direction at right angles to the second wrapper, the overlapping of the sides of the first wrapper occurring on the face of the tablet opposite to the overlapping of the sides of the second wrapper, and also both the first and the second wrappers have their end parts separately and completely folded.

Having thus described the form of the inner and outer wrappers in which the tablet is to be inclosed, and the folding of the two wrappers on to a tablet, which is to be car- 105

ried out by the machine, and having outlined broadly the members by which such wrapping operations are accomplished, a definite example of construction of a machine according to this invention will now be described with further reference to the accompanying drawings.

Fig. 1 is a general side elevation of the machine, partially in section, one of the side frames being removed and portions of the mechanism omitted. Fig. 2 is a similar view with further parts in section and Fig. 3 is a plan view of the machine.

Figs. 17 and 18 are vertical sections in two different positions of the reciprocative carriage drawn to a larger scale than the previous figures, together with some adjacent parts, and Fig. 19 is a plan view of the apparatus in the position of Fig. 17. Fig. 20 is a vertical section of the plunger shown at Fig. 2 for carrying up the unwrapped tablet, and Fig. 21 is a sectional elevation at right angles to Fig. 20, illustrating also the mechanism for feeding the tablets on to the plunger. Fig. 22 is an elevation in a plane at right angles to that of Fig. 2 showing the cutting device for severing the inner wrapper from the web, and Fig. 23 is a plan view of the same. Fig. 24 is a sectional elevation illustrating the means for dealing with the pile of wrappers from which the second wrapper for each tablet is taken, and Fig. 25 is a plan view of the storage box of Fig. 24. Fig. 26 is a detail plan view showing mechanism for giving intermittent angular motions to the carrier of the second wrapper. Fig. 27 shows in sectional elevation in a plane at right angles to that of Figs. 1 and 2, and at the same time drawn to a larger scale, the mechanism for completing the folding of the first wrapper and for folding the second and outer wrapper. Fig. 28 is a plan view of the same, a portion being broken away to show other parts, and Fig. 29 is a transverse section taken about the line X-Y of Fig. 28. Fig. 30 shows an elevation of the tucking fingers which tuck in the ends of the second wrapper as at Fig. 13, and Fig. 31 shows the lower plunger of the wrapping mechanism dealing with the second wrapper.

Referring to the general views of the drawings, Figs. 1, 2 and 3, the framework of the machine comprises a horizontal table supporting various mechanisms hereafter described, which table is carried by suitable framework, such as illustrated, and the tablets to be wrapped, such as A Fig. 4, are placed upon a traveling belt 1, Fig. 3, with the sides of the tablets at right angles to the direction of travel, and the tablets are thereby carried forward; the forward part of the belt 1 is shown at Fig. 21, the carrying pulley receiving a step-by-step motion by means

of a ratchet mechanism 37, operated through a lever 38 pivoted at 35, Fig. 2, receiving motion by means of a cam on a shaft 34 carried in bearings in the framework, and revolved through the medium of toothed wheels from a driven shaft 33.

The tablets pass one after the other from the belt 1, Fig. 21, by a bridge piece 39 on to the top of a plunger 3. The plunger 3 receives vertical movement at proper times by means of a lever 40, Fig. 2, pivoted at 35 and operated by a cam on the cam shaft 34.

The plunger 3 is situated immediately below an aperture 4, Fig. 2, in a table 5, on to which the inner wrappers B (Fig. 4) are fed from a roll 6; the feed takes place by the web 6 passing between feed rollers 7, Figs. 1 and 2, which are intermittently operated at proper times by a ratchet mechanism 41 operated from a lever pivoted at 35 and actuated by a cam on the shaft 34, the ratchet 85 operated shaft carrying a spur wheel gearing with the lower feed roller 7, and so, intermittently, the web of the inner wrapper is fed along the table 5.

The foremost piece of the web on the table 5 is cut off by a knife 8, this piece being located over the aperture 4 of the table 5; the knife 8 is shown detached at Figs. 22 and 23 from which it will be seen that the knife is pivoted and that the wrapper passes beneath a stationary top guide 8^x and is operated by a connecting rod, the lower end of which is pivoted to a lever 42, Fig. 1, the latter turning about the center 35 and being operated through the medium of a cam on the shaft 34. The knife is held up to its work by a spring on its pivot, as indicated in the plan view at 23.

Above the table 5, in slides 9, is mounted the longitudinally reciprocative carriage 10, Figs. 1 and 2, and which is shown in further detail at Figs. 17, 18 and 19. As will be observed in Figs. 17 to 19, the forward end of the carriage is forked, and each fork has a downward extension 12 and a rearward bearing surface 11, while the forward ends of the fork carry pivoted fingers 11^x, held rearwardly by springs, as shown, and limited in their rearward movements by upwardly extending arms carrying set screws which will bear, in the position shown in the drawings, on the ends of the forked members, so that the fingers 11^x will yield in a forward direction.

A horizontal slide 14 is provided below the carriage 10 having a downwardly extending guide plate 13^x located opposite to a stationary guide plate 13 carried on the table 5, and the slide 14 is operated by a lever 43 (Fig. 2) pivoted at 35^x, Fig. 1, actuated by a cam on the shaft 34.

Above the slide 14 and below the carriage 10 is a horizontally movable arm 16, having two upwardly extending parts 16^x engaging

in slots 10* in the carriage 10, and a tension spring 17, extending between one of the upward extensions 16* of the arm 16 and the carriage 10, tends to hold the carriage 10 against a stop 9*.

Extending forwardly from the arm 16 are two end tucking members 15, and the arm 16 is connected by a link to a lever 44 pivoted at 35*, Fig. 1, and actuated by a cam 16 on the shaft 34.

The mechanism, so far as has already been described, effects the operations upon the inner wrapper B up to and including the stages of wrapping illustrated at Figs. 4 to 8 of the drawings, and therefore the operation of this part of the mechanism will now be described.

When the forward end of the web 6, Fig. 2, supplying the inner wrappers, has advanced to the proper distance over the aperture 4 of the table 5, the knife 8 is operated and cuts off, from the web, the foremost inner wrapper.

The mechanism being in the position shown at Fig. 2, the vertical plunger 3, bearing upon its end the tablet to be wrapped, is raised, and carries the tablet with the wrapper lying upon its upper surface between the downwardly extending guide plate 13* and the fixed guide plate 13, thus folding down, over the ends of the tablet, the two ends B¹, B², Fig. 5, of the wrapper; still advancing upward, the plunger 3 carries the tablet and wrapper upon it between the rearward bearing surface 11 of the carriage 10 and the pivoted fingers 11* carried upon the same carriage, so that the downward extensions 12 of the forked members of the carriage 10 fold down the sides C of the wrapper, Fig. 5, on to the sides of the tablet. The tablet is thus held in the fork of the carriage 10 with its wrapper folded, in the position shown at Fig. 5, by the pressure of the pivoted fingers 11*. While in this position, the horizontal slide 14, Fig. 17, is moved forwardly, passing beneath the tablet and so folding the downwardly extending rear end B¹ of the wrapper on to the under surface of the tablet, as is shown at Fig. 6. The arm 16 is then advanced from the position shown at Fig. 17 to that shown at Fig. 18, whereby the tucking members 15 of the arm 16 act upon the wrapper and fold the corner pieces D, Fig. 6, on to the folded sides of the wrapper into the position shown at E, Fig. 7. The upward extensions 16* being now, as at Fig. 18, at the forward ends of the slots 10* in the carriage 10, the continued advance of the arm 16 moves the carriage 10 in a forward direction, the carriage 10 carrying with it the tablet wrapped with its inner wrapper in the stage shown at Fig. 7. This continued advance of the arm 16, carrying with it the

carriage 10, carries the forward depending end B², Fig. 7, of the wrapper over the upper surface of the forward stationary guide plate 13, and folds the end B² of the wrapper on to the lower surface of the tablet, as at Fig. 8, and the carriage 10 carrying the tablet with the inner wrapper folded so far thereon, as stated, continues its advance and the inner wrapper is still further folded on to the tablet and the outer wrapper applied and folded by wrapping mechanism 75 to be described.

The outer wrappers H are carried in the form of a pile, cut to the requisite size and rectangular shape, the pile 18, Fig. 1, being contained in a box 19, the details of which are shown at Figs. 24 and 25. Referring to Figs. 24 and 25, the wrappers 18 are supported upon a table 45 carried by a plunger 46, to which a lifting tendency is imparted by a weight 47 suspended from cords 48 passing over pulleys 49, one of which is shown in dotted lines at Fig. 24, the cords being attached to an arm on the lower end of the plunger 46. 50 is a brake pivoted at 51 to the sleeve through which the plunger 46 slides, and has a downwardly extending arm 52 carrying a tappet 53 which, when acted upon, releases the brake. The brake so acts that when applied, which is the normal condition, it permits the table 45 to slowly rise, and the pile of wrappers are normally held up against corner pieces 54 of the box, Fig. 25.

Carried in suitable bearings of the framework is a vertical shaft 55, Fig. 1, capable of vertical but not of rotary motion, and which is vertically moved at proper times by a lever 56 operated by a cam on the shaft 34, and at its upper end the shaft 55 carries a plunger 23. The shaft 55 passes through a sleeve 57, Fig. 1, which latter has fixed on its upper end a disk 21 which is to receive step-by-step rotation, and which also is to be raised and lowered, and this disk carries three sets of downwardly depending feet 20, and three pairs of end tuckers 22 which are fixed to the said disk. The sleeve 57 is raised and lowered at proper times by a lever 58, Fig. 1, pivoted at 35' and operated by a cam on shaft 33, and the sleeve 57 is fitted with a pinion 59 engaging a toothed wheel 60, see Fig. 26, the face of which is of sufficient width to permit of the vertical motion of the sleeve 57 without the teeth of the pinion 59 becoming disengaged from the 120 teeth of the spur wheel 60.

The spur wheel 60 is carried by a shaft 61 revolvable in bearings in the framework and passing through the horizontal table thereof, adjacent to the upper surface of which the shaft 61 is fitted with ratchet mechanism 62 operated by a connecting rod 63 by means of a lever 64, see Fig. 2, receiving

motion from a cam on the shaft 34. A spring retained pivoted arm 65, Fig. 26, is provided, having a tooth 66 taking into one or other of three notches in a disk 67 carried by the sleeve 57, in order to define the positions of the sleeve 57 and consequently of the disk 21.

On the main table of the framework and extending beneath the disk 21 is a box, carrying rollers 68, Figs. 2 and 3, for supplying adhesive to the ends of the feet 20, the rollers being driven by means of belts, as shown at Fig. 2, from a pulley on the shaft 33.

It will be observed from Fig. 3 that when one set of feet 20 with the tucking fingers 22, are located over the pile of outer wrappers 18, another set of feet and pair of tucking fingers carried by the disk will be opposite the carriage 10.

The operation of taking an outer wrapper from the pile is as follows:—During the step-by-step rotation of the disk 21, the ends of the feet 20 pass over the roller 68, Fig. 2, and receive a supply of adhesive, and upon those feet arriving above the pile of wrappers, the disk 21 is lowered by the lever 58, Fig. 1, and the feet press upon the uppermost wrapper and depress the pile of wrappers against the action of the weight 47, Fig. 24. During the descent of the feet of the disk 21, the lever 58, Figs. 1 and 24, contacts with the tappet 53, Fig. 24, and momentarily releases the brake 50, and immediately the pile of wrappers receive an upward impulse by the action of the weight, and the brake again becomes applied, so insuring the uppermost wrapper firmly adhering to the feet 20, and then the disk 21 is raised carrying the wrapper with it, while the pile of wrappers from which it is taken rise more slowly, so that the uppermost wrapper, seized by the feet, is flicked past the corner pieces 54, Fig. 25, and carried away from the pile. The disk 21 then receives a partial rotation, bringing the wrapper opposite to the carriage 10 and holding it in a horizontal position, the plunger 23 being in a raised position.

The tablet carried by the carriage 10, and so far inclosed in the inner wrapper as has been described with reference to Fig. 8, is then advanced forward, the corners F, Fig. 8, of the wrapper being thus acted upon by the tucking fingers 22 of the disk 21 and so folded on to the folded side C of the inner wrapper into the position as shown at Fig. 9, and the tablet so wrapped in the inner wrapper is now to be subjected to the mechanism by which the folding of the inner wrapper is completed, and by which the folding of the outer wrapper thereon is carried out, and this mechanism will now be described.

Opposed to the upper plunger 23 is a lower plunger 24, Fig. 2, capable of vertical

sliding motions through an aperture in a table 26, see also Fig. 31, and operated through the medium of a link 69 connecting the plunger with a lever 70, receiving motion from a cam on the shaft 33.

Upon the table 26 is located folding mechanism, which is shown detached and upon a larger scale at Figs. 27, 28 and 29, by means of which the folding of the inner wrapper is completed and the folding of the outer wrapper around the already inclosed tablet effected, and which will now be referred to.

As a lateral continuation of the table 26 there is a trough-like structure 29 comprising spring-held sides 71, Fig. 28, and a base, and having a lid 28, the enlarged end of which 72 terminates immediately before the lower plunger 24, and upon the table 26 on the opposite side of the plunger 24 there are guides 73 containing certain sliding members now to be referred to. One of such members consists of a reciprocating slide 25 in a position so that its lower surface can slide over the top of a tablet when the tablet rests upon the plunger 24 in the position shown at Fig. 27, and which we will term a top slide.

Between the guides 73 is a horizontal pusher 27 bifurcated at its forward end, as shown at Fig. 28, so as to pass on each side of the plunger 24 when the latter is in a raised position, and there is further carried outer horizontal tucking fingers 31, Fig. 28, one upon each side of the pusher 27, the tucking fingers being connected together at their rear.

The reciprocating slide 25, the pusher 27 and the tucking fingers 31 are each operated at proper times by links and connecting rods 74, 75 and 76 through the medium of rock levers, such as 77, Fig. 1, operated by cams on the shaft 33.

Downwardly moving tucking fingers 30 are provided at each side of the cover end 72, these being operated, as shown at Fig. 30, by means of a link 78 and lever 79 operated by a cam on the shaft 33. Rearward of the tucking fingers 30 there are two blocks 32, the lower surfaces of which stand at a short distance from the face of the table 26, as shown at Fig. 27.

Rearward of the blocks 32 the sides of the trough extend downwardly and present a lower inclined edge, as at 80, Fig. 27, there being a slight clearance space between the edges of the base of the trough and the vertical inner faces of the plates 80.

Rearward of the plates 80, the sides of the trough have horizontal inwardly extending wings 81 at the base part, as shown at Fig. 28, and then the continuation of the trough consists of the base 82, the spring-held sides 71 and the top cover.

The operation of this mechanism for com-

pleting the folding of the inner wrapper and for dealing with the second wrapper is as follows:—The carriage 10 having been slid, as before stated, toward the left hand 5 from the position at Figs. 1 and 2, now carries the tablet partly wrapped in the inner wrapper in the condition shown at Fig. 9, and so holds the said tablet immediately above the outer wrapper H, which 10 latter is held by the adhesive on to the feet 20, and the tablet is also in position immediately beneath the plunger 23. The lower plunger 24 then rises to beneath the wrapper and tablet, and the upper plunger 23 comes down on to the top of the tablet, 15 and then both plungers descend and carry the tablet and the wrapper beneath it, into the position shown by dotted lines at Fig. 27; thus causing the sides H¹, H² of the outer wrapper to be turned upward on to the sides of the tablet, as shown at Fig. 10, simultaneously folding up the outstanding flaps J, Fig. 9, of the inner wrapper. The rear upstanding side H² of the outer wrapper 20 is then folded over into the position shown at Fig. 11 by the forward advance of the reciprocating slide 25, and the tablet and wrapper are then pushed by the bifurcated pusher 27 (Fig. 28) beneath the end 25 72 of the trough, thus folding down the forward upstanding side H¹ of the wrapper into the position shown at Fig. 12. The tucking fingers 30 (Figs. 28 and 30) then descend and tuck in the end portions H³ 30 (Fig. 13) during which the lower plunger 24 rises to receive another tablet. Upon the rise of the tucking fingers 30, the horizontally sliding tucking fingers 31 advance and tuck in the rearward corners K of the 35 wrapper, as at Fig. 14, and then retire.

Another tablet having been brought by the plunger 24 into the dotted position at Fig. 27, then upon this second tablet being advanced by the pusher 27, the first tablet 40 dealt with is forced between the blocks 32, so tucking in the forward corners L (Fig. 45), and the extending flaps M pass beneath the lower surfaces of the blocks 32; and as the tablet advances the extending flaps M 45 are acted upon by the inclines of the side plates 80, and are so turned vertically downward. Upon arriving at the horizontal wedge-shaped plates 81, the said downwardly extending flaps M are turned beneath the package as at Fig. 16, and in due course the tablet thus completely wrapped, in an inner and an outer rectangular wrapper, arrives at the delivery end of the trough in a finished condition.

60 What I claim as my invention and desire to secure by Letters Patent is:—

1. In a machine for folding a rectangular wrapper about a rectangular tablet, and in combination, a frame-work, a reciprocating

carriage therein adapted to receive and convey a tablet, means for supporting horizontally a rectangular wrapper below the said tablet in the said carriage when the latter is adjacent the forward end of its travel, an upper and a lower plunger located 65 respectively above and below the said tablet in the said carriage when the latter is in the position aforesaid, means for operating said plungers to cause the lower plunger to rise beneath the wrapper to support the tablet 70 and then to cause both the upper and lower plungers to descend and carry the said tablet and wrapper therewith, a trough member having a forwardly projecting lid and a slide carried in guides between the ends of 75 which lid and slide the said tablet and wrapper pass during the descent of the tablet to fold upwardly the sides of the wrapper against the sides of the tablet, means for then folding down one side of the wrapper 80 over the top of the tablet, means for advancing the tablet through the said trough member to fold down the opposite side of the wrapper on the top of the tablet, means for folding down the upper projecting ends of 85 the wrapper onto the ends of the tablet, means for tucking in the rear and forward corners of the wrapper against the ends of the tablet, and means for folding the then outstanding flaps of the wrapper against 90 the under surface of the tablet.

2. In a machine for folding a rectangular wrapper about a rectangular tablet, and in combination, a frame-work, a wrapper receptacle, a revoluble carriage, a plurality of 95 sets of transfer members secured to the revoluble carriage, a reciprocating carriage, means for actuating the same, means for actuating the revoluble carriage so as to cause the transfer members to take a wrapper 100 from the receptacle and place the same beneath a tablet in the said reciprocating carriage when the latter is adjacent the forward end of its travel, an upper and a lower plunger located respectively above and below the said tablet in the said carriage when the latter is in the position aforesaid, means for operating said plungers to cause the lower plunger to rise beneath the wrapper 105 to support the tablet and then to cause both the upper and lower plungers to descend and carry the said tablet and wrapper therewith, a trough member having a forwardly projecting lid and a slide carried in guides, between the ends of which lid and slide the 110 said tablet and wrapper pass during the descent of the tablet to fold upwardly the sides of the wrapper against the sides of the tablet, means for then folding down one side of the wrapper over the top of the tablet, means for advancing the tablet through the said trough member to fold down the 115 opposite side of the wrapper on the top of the 120 tablet, means for advancing the tablet through the said trough member to fold down the opposite side of the wrapper on the top of the 125 tablet.

the tablet, means for folding down the upper projecting ends of the wrapper onto the ends of the tablet, means for tucking in the rear and forward corners of the wrapper 5 against the ends of the tablet, and means for folding the then outstanding flaps of the wrapper against the under surface of the tablet.

In witness whereof I have hereunto set my hand in the presence of two witnesses.

FREDERICK GROVER.
